SAFETY HELMET

John L. Marchello, Ann Arbor, Calif., assignor to Joseph Buegeleisen Company, Southfield, Mich., a corporation of Michigan

Filed Oct. 23, 1964, Ser. No. 82,296

Term of patent 14 years

(Cl. D3—13)

FIG. 1 is a top plan view of a safety helmet showing my new design;

FIG. 2 is a side elevational view thereof, the opposite side being a mirror image thereof; and

FIG. 3 is a front elevational view thereof.

I claim:

The ornamental design for a safety helmet, as shown and described.
